UNITED STATES PATENT OFFICE.

HENRY P. ROBERTS, OF BOSTON, MASSACHUSETTS, ASSIGNOR TO JOHN I. TAYLOR, OF DEDHAM, MASSACHUSETTS.

DESIGN FOR A POTATO MASHER AND RICER.

57,862.

Specification for Design.

Patented May 10, 1921.

Application filed November 28, 1917. Serial No. 204,473. Term of patent 3½ years.

To all whom it may concern:

Be it known that I, HENRY P. ROBERTS, a citizen of the United States, residing at Boston, in the county of Suffolk and State of Massachusetts, have invented a new, original, and ornamental Design for a Potato Masher and Ricer, of which the following is a specification, reference being had to the accompanying drawing, forming a part thereof.

The drawing is a perspective view of a potato masher and ricer showing my new design.

I claim:

The ornamental design for a potato masher and ricer as shown.

HENRY P. ROBERTS.

Witness:

ALICE H. MORRISON.
